ORNAMENTATION OF KNIT FABRICS.

Spec. S. 1884

UNITED STATES PATENT OFFICE.

JEREMIAH P. HARRIMAN, OF WOONSOCKET, RHODE ISLAND.

DESIGN FOR THE ORNAMENTATION OF KNIT FABRICS.

SPECIFICATION forming part of Design No. 18,364, dated June 5, 1888.

Application filed March 10, 1888. Serial No. 266,885. Term of patent 14 years.

To all whom it may concern:

Be it known that I, JEREMIAH P. HARRIMAN, a citizen of the United States, and a resident of Woonsocket, county of Providence, and State of Rhode Island, have invented and produced a new and original Design for Surface Ornamentation of Knitted Fabrics, of which the following is a full, clear, and exact description, reference being had to the accompanying photographic illustration, forming a part hereof, in which is represented a portion of a fabric with my design applied thereto.

My design is intended for application generally to all forms of knitted fabrics to which it is desired to impart an ornamental appearance; and it consists in a series of stripes arranged diagonally of the fabric in respect to the successive rows or courses of loops composing the same, with short parallel stripes interposed between them and disposed longitudinally of the fabric as respects such rows or courses of loops, all as will hereinafter more fully appear.

In the photographic illustration the main stripes are shown at A A, &c., and the short parallel interposed stripes at B B, &c. The stripes A A, &c., are composed of a middle denticulated stripe with a small zigzag stripe arranged upon either side thereof, forming a group of three, which are repeated as often as desired and disposed in diagonal relation with respect to the component rows or courses of loops composing the fabric, the distance between the adjacent groups being sufficient to

admit of the interposition of the short parallel stripes B B, &c. These latter stripes, like the preceding, are arranged in parallel relation with respect to one another at the required distance apart, and are disposed longitudinally of the fabric as regards the successive rows or courses of loops composing the same between the groups of stripes A A, &c., meeting the latter at an oblique angle, the arrangement being such that a series of groups of continuous stripes is shown disposed diagonally across the fabric, with short parallel stripes interposed between them and lying longitudinally of the same.

Having described my invention, what I claim as new, and desire to secure by Letters Patent of the United States, is—

The design for surface ornamentation of knitted fabrics, consisting of a series of groups of stripes comprising a middle denticulated stripe and two outside zigzag stripes arranged diagonally of the fabric with respect to the successive rows or courses of loops composing the same, with short parallel stripes interposed between such groups and lying longitudinally of the fabric as regards such rows or courses of loops, substantially as shown and described.

In testimony whereof I have hereunto set my hand this 27th day of February, 1888.

JEREMIAH P. HARRIMAN.
